UNITED STATES PATENT OFFICE

105,143

DESIGN FOR A KNITTED CAP OR SIMILAR ARTICLE

Ike Schlesinger, East Orange, N. J.

Application April 18, 1936, Serial No. 62,198

Term of patent 14 years

To all whom it may concern:

Be it known that Ike Schlesinger, a citizen of the United States and resident of East Orange, in the county of Essex and State of New Jersey, has invented a new, original, and ornamental Design for a Knitted Cap or Similar Article, of which the following is a specification, reference being had to the accompanying drawing, forming part thereof, in which:

Fig. 1 is a side perspective view of a knitted cap embodying my design;

Fig. 2 is a front perspective view thereof.

I claim:

The ornamental design for a knitted cap or similar article substantially as shown.

IKE SCHLESINGER.
